US00D967175S

(12) **United States Design Patent** (10) Patent No.: **US D967,175 S**
(45) Date of Patent: **** Oct. 18, 2022**

(54) **DISPLAY PANEL WITH GRAPHICAL USER INTERFACE**

(71) Applicant: **LG ELECTRONICS INC.**, Seoul (KR)

(72) Inventors: **Soomin Shim**, Seoul (KR); **Yongdeok Lee**, Seoul (KR); **Hyeran Jang**, Seoul (KR); **Hwajun Oh**, Seoul (KR)

(73) Assignee: **LG ELECTRONICS INC.**, Seoul (KR)

(**) Term: **15 Years**

(21) Appl. No.: **35/512,996**

(22) Filed: **May 24, 2021**

(80) **Hague Agreement Data**

Int. Filing Date: **May 24, 2021**

Int. Reg. No.: **DM/214586**

Int. Reg. Date: **May 24, 2021**

Int. Reg. Pub. Date: **Nov. 26, 2021**

(30) **Foreign Application Priority Data**

Dec. 8, 2020 (KR) 30-2020-0060501

(51) **LOC (13) Cl.** **14-04**

(52) **U.S. Cl.**

USPC **D14/486**

(57) **CLAIM**

The ornamental design for a display panel with graphical user interface, as shown and described.

DESCRIPTION

The file of this patent contains at least one drawing executed in color. Copies of this patent with color drawing(s) will be provided by the Office upon request and payment of the necessary fee.

1. Display panel with graphical user interface

1.0 : Front

The broken lines are for the purpose of illustrating portions of the display panel with a graphical user interface that form no part of the claimed design.

**1 Claim, 1 Drawing Sheet
